UNITED STATES PATENT OFFICE.

NICHOLAS WENDEL, OF BROOKLYN, NEW YORK.

HAND BAG.

Application filed August 7, 1922. Serial No. 580,244.

To all whom it may concern:

Be it known that I, NICHOLAS WENDEL, a citizen of the United States, and a resident of the city of New York, borough of Brooklyn, in the county of Kings and State of New York, have invented a new and Improved Hand Bag, of which the following is a full, clear, and exact description.

This invention has relation to hand bags and has particular reference to an improvement 10 in the construction of ladies' hand bags or pocketbooks.

One of the principal features of the present invention resides in the manner of attaching the outer covering material, lining and gussets to the frame in order to minimize the wear thereon.

As a further object the invention contemplates a hand bag structure in which the gussets are entirely concealed, housed and protected by the frame when the same is in closed position.

The invention further aims to provide a hand bag construction which affords a wider opening of the compartments to admit of ready access thereto for removing and placing articles therein.

As a still further object the invention contemplates a hand bag in which the frame jaws extend entirely throughout the height 30 of the bag to afford a protection for the body and to lend greater strength to the structure.

As a still further object the invention aims to produce a hand bag or pocketbook which is extremely simple in its construction, inexpensive to manufacture, and which is strong and durable.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

50 In the drawings—

Figure 1 is a front view of a hand bag constructed in accordance with the invention, illustrating the same in closed condition.

55 Fig. 2 is a side view thereof.

Fig. 3 is a plan view of the same in open position.

Fig. 4 is a side view of the same in open position.

Fig. 5 is an enlarged detail sectional fragmentary view taken approximately on the line 5—5 of Fig. 3.

Fig. 6 is an enlarged fragmentary detail transverse sectional view taken approximately on the line 6—6 of Fig. 3.

Fig. 7 is an enlarged detail sectional view taken approximately on the line 7—7 of Fig. 1.

Referring to the drawings by characters of reference, 10 and 11 designate a pair of frame jaws which are pivotally connected as at 12 and are provided with interengaging clasp elements 13 and 14 for retaining the same in closed condition. The frame jaws are of channel construction and are designed to receive in the channel portion thereof the outer covering material 15, the inner lining material 16 and the free edges 17 of the plaited gussets 18, which elements are preferably held within the channel portion of the jaws by a suitable adhesive such as glue, cement, or the like. A partition 19 is secured at its opposite edges to the central plait 20 of each gusset 18 and said partition consists of two strips of material 21 and 22 which are fastened together at their lower ends by the stitching 23 with the upper ends free for relative separation to provide therebetween a change pocket 24. The outer faces of the strips 20 and 21 are covered by a facing material 25 and the change pocket 24 is provided with a lining 26. Suitable channeled reinforcing bars 27 embrace the upper free edges of the strips 21 and 22 as well as the lining 26 and the facing strips 25. The central or intermediate plait 20 serves as gussets and side walls for the change pocket 24.

A covering and retaining flap 28 is secured by the stitching 29 to the strip 20 adjacent its upper ends and is adapted to extend over the upper edge of the strip 22. The free end of the flap 28 is provided at one extremity with the socket member 30 of a separable fastening element, the head member 31 of which is attached to the strip 22 whereby the flap when fastened by the separable fastening elements prevents accidental opening of the change pocket. The central partition 19 serves to subdivide the bag body into separate segmental compartments 32 and 33, 110

while the plaited gussets 18 constitute means for limiting the opening of the bag. Due to the fact that the frame jaws extend throughout the full height of the bag body, a wide opening of the compartments 32 and 33 may be effected to facilitate the placing and removal of articles within and from the bag body. A suitable strap 34 may be attached at its opposite ends as at 35 to one of the frame jaws for the purpose of providing a handle for carrying the bag.

I claim:

1. As a new article of manufacture, a hand bag comprising a bag body and pivoted frame jaws extending throughout the height of the bag body, plaited gussets at the opposite sides of the bag body, and a central partition secured at its opposite edges to the central plait of each gusset to provide separate segmental compartments in the bag body, the said central partition consisting of a double wall the plies of which are

stitched together medially and transversely to leave the same open at the upper end defining therebetween together with the central 25 gussets plait, a change pocket.

2. As a new article of manufacture, a hand bag comprising a bag body and pivoted frame jaws extending throughout the height of the bag body, plaited gussets at the opposite sides of the bag body, a central partition secured at its opposite edges to the central plait of each gusset to provide separate segmental compartments in the bag body, the said central partition consisting of a double 35 wall the plies of which are stitched together medially and transversely to leave the same open at the upper end defining therebetween together with the central gussets plait, a change pocket, and a flap secured to one of 40 said walls and detachably engageable with the opposite wall for retaining the change pocket in closed condition.

NICHOLAS WENDEL.
